UNITED STATES PATENT OFFICE.

GLEN SWITZER, OF MACON, MISSOURI.

LOOSE-LEAF BINDER.

1,178,886.

Specification of Letters Patent. Patented Apr. 11, 1916.

Application filed March 22, 1915. Serial No. 16,219.

To all whom it may concern:

Be it known that I, GLEN SWITZER, a citizen of the United States, residing at Macon, in the county of Macon and State of Missouri, have invented certain new and useful Improvements in Loose-Leaf Binders; and I do declare the following to be a full, clear, and exact description of the invention, such as will enable others skilled in the art to 10 which it appertains to make and use the same.

This invention relates to loose leaf binders and more particularly to loose leaf check covers or binders.

15 The object of the invention is to provide a loose leaf binder, the posts of which are adjustable to engage leaves having holes spaced different distances apart or at different places.

20 Another object is to provide a binder of this character especially designed as a check binder and which is so constructed that there will be no covering over the stub end of the checks at the back.

25 With these and other objects in view, the invention consists of certain novel features of construction, and the combination and arrangement of parts as will be more fully described and claimed.

30 In the accompanying drawings: Figure 1 represents an edge view taken from one end of this improved binder and shown in operative position; Fig. 2 is a transverse section taken on the line 2—2 of Fig. 1; Fig. 3 is a 35 longitudinal section taken on the line 3—3 of Fig. 2; Fig. 4 is a horizontal section taken on the line 4—4 of Fig. 3; Fig. 5 is a plan view with one leaf or cover member of the binder removed, and Fig. 6 is a per- 40 spective view of the binder and the sheets to be disposed therein arranged in juxtaposition ready for assembling.

In the embodiment illustrated, this binder is constructed of two separably connected 45 leaves or backs 1 and 2 which may be composed of any suitable stiff material and covered with cloth, leather, or other desired fabric.

Secured to the rear edge of the back 1 and 50 extending throughout the width thereof is a metal post supporting member 3 here shown in the form of a plate folded inter-

mediately of its ends forming leaves 4 and 5 which are spaced apart a sufficient distance to permit the heads of the posts to be 55 described to move freely between them. The leaf 5 is considerably longer than leaf 4 and overlaps the outer face of the rear end of the back land is secured thereto by riveting or otherwise, while the narrower plate 4 has its free edge abutting against the rear edge of the back 1, as is shown clearly in Figs. 1 and 3. The plate 4 is disposed on the inner face of the back 1 and is arranged substantially flush with the 60 inner face thereof and is provided with longitudinally extending key hole slots 6 and 7 extending in opposite directions with the rounded portions 8 arranged near the center of the plate 4 and the slotted portions 9 thereof extending nearly to the outer ends of said plates. These slots are designed to receive the leaf supporting posts 10 and 11 which are here shown provided with the usual disk-like heads 11 with 65 shanks 12 extending centrally from one face thereof and threaded at their outer ends to receive clamping nuts 13 which are preferably milled on their edges to facilitate their turning. The heads of these posts are of 70 slightly less diameter than the rounded openings 8 of the slots 6 and 7 to permit said heads to enter said openings 8 and to slip between the leaves 4 and 5 in the slots 6 and 7 so that they may be adjusted at any 75 desired point within the slots to adapt them to receive checks or other sheets 14 which are provided at their rear ends with apertures for the passage therethrough of the shanks of these posts. The other back 2 is 80 shown of the same width and size as the back 1 and has a flexible hinge member 15 secured to its rear end and which is here shown composed of a leather strip of double thickness and of the same width or slightly 85 greater width than said back 2 so that the opposite edges thereof may be folded over the edges of said back and secured. This strip 15 may be of any desired length and is provided near its free edge with a pair of 90 transversely extending alined slots 16 and 17 spaced apart at their inner ends and which are adapted to pass over and slidably receive the posts 9 and 10 to permit said 95 100

posts to be adjusted transversely relatively to said hinge strip. A clamping plate 18 is designed for coöperation with the posts 6 and 7 and is here shown of a length corresponding to the width of the backs 1 and 2 and which may be of any suitable or desired width, being here shown of a width corresponding to the width of the leaf 4 of plate 3. This clamping plate 18 is provided with longitudinally extending slots 19 and 20 spaced apart at their inner ends and which are adapted to fit over and slidably receive the posts 9 and 10 after said posts have been passed through the apertures in the checks 14 or other sheets 14 which are to be clamped between the backs 1 and 2, and through the slots 16 and 17 in strip 15 of back 2, and when said parts have been so disposed this plate 18 is engaged with the free ends of the posts 9 and 10 and then screwed on to the threaded ends of said posts into clamping engagement with the plate 18, thereby forcing said plate downwardly on the checks 4 and securely binding them between the plates 18 and the rear end of back 1 so that said backs 1 and 2 are thus securely held together with the sheets 14 clamped between them. The back 2 is designed as a protective cover for the outermost check or sheet 14 and may be readily opened to expose said sheet.

From the above description it is thought that the operation of the device will be obvious but a brief description of the assembling of the parts will be given below; to wit: When it is desired to assemble the backs 1 and 2 and to mount between them checks or other sheets 14, the heads of the studs 9 and 10 are first inserted in the rounded apertures 8 at the inner ends of the key hole slots 6 and 7 and then moved into said slots the desired distance to position them to receive the apertures in the checks or sheets which they are designed to connect. After they have been so disposed, the device is ready to receive the checks 14 which are engaged with the posts by threading the apertures therein on the posts and after the desired number of checks have been so arranged, the slotted leather hinge 15 is engaged with the posts by passing them through the slots 16 and 17 therein. The clamping plate 18 is passed over the posts 9 and 10 with the threaded ends of said posts projecting through the slots in said plate, and the nuts 13 are then secured to the ends of the posts and the parts reliably clamped in operative position where they will be held until the nuts are loosened and the parts disconnected. By so arranging these parts with the leather strip 15 disposed above the outermost check 14, the rear ends or stubs of the checks will be uncovered as shown in Figs. 1 and 3 to adapt said studs to project beyond the back members 1 and 2 should

the apertures therein be formed at points spaced inwardly from said rear edges such a distance as to cause these edges to project beyond the backs after the posts 9 and 10 have been inserted therein.

70

I claim as my invention.

1. A loose leaf binder comprising two back members, one of which is provided with a member having transversely extending key hole slots therein, headed posts slidably mounted in said slots, the other back member being provided with a flexible hinge member having openings for engagement with said posts, a coöperating clamping plate having longitudinally extending slots 75 for engagement with said posts, and nuts mounted on the free ends of said posts for holding the parts in adjusted position.

80

2. A loose leaf binder comprising separable back members, one of which has a folded plate secured to the rear end thereof, the inner portion of said plate being spaced from the outer portion and provided with alined transversely extending key hole slots, headed posts removably and slidably engaged in said slots, a clamping plate having longitudinally extending slots for the passage therethrough of said posts, and means engaging said posts for holding said members in adjusted position.

85

3. A loose leaf binder comprising two backs, one of which has posts adjustable transversely thereof and the other provided with a flexible hinge member having transversely extending slots for engagement with said posts, a longitudinally slotted clamping plate for engagement with said posts, the outer or free ends of said posts being threaded, and nuts for engagement with said threaded ends to clamp the parts in operative position.

90

4. A loose leaf binder comprising a back member having a metal plate secured to its rear end, said plate being folded inwardly with the edge of its inner member abutting against the edge of said back member, said folded plate member being provided with transversely extending key hole slots, headed posts slidably engaged with said slots, another back member having a flexible hinge provided with transversely extending slots for the passage therethrough of said posts, a slotted clamping plate for engagement with said posts, and nuts engaged with the free ends of said posts outside said clamping plate.

100

5. A loose leaf binder comprising two stiff back members, a transversely folded metal plate secured to the inner end of one of said members, one of the members of said plate being longer than the other and secured to the outer face of said back, the shorter member having its edge abutting the edge of said back member and provided with transversely extending key-hole slots, headed posts slid-

able in said slots, the other back member having a flexible hinge member secured to its inner end and provided with transversely extending slots for the passage therethrough of said posts, a slotted clamping plate for engagement with said posts, and nuts engaged with the free ends of said posts outside said clamping plate.

In testimony whereof I have hereunto set my hand in presence of two subscribing ¹⁰ witnesses.

GLEN SWITZER.
